UNITED STATES PATENT OFFICE.

ERNST HURLIMANN, OF ZUCHWIL, NEAR SOLOTHURN, SWITZERLAND, ASSIGNOR TO
THE FIRM SCINTILLA, OF SOLOTHURN, SWITZERLAND.

MECHANISM FOR REGULATING THE POINT OF IGNITION IN MAGNETO-ELECTRIC IGNITION APPARATUS.

1,349,278.

Specification of Letters Patent. Patented Aug. 10, 1920.

Application filed March 23, 1918. Serial No. 234,886.

To all whom it may concern:

Be it known that I, ERNST HURLIMANN, a citizen of the Swiss Republic, residing at Zuchwil, near Solothurn, in the Canton of Solothurn, Switzerland, have invented certain new and useful Improvements in Mechanism for Regulating the Point of Ignition in Magneto-Electric Ignition Apparatus, of which the following is a specification.

10 A number of different mechanisms have already been proposed for the purpose of regulating at will within certain limits the point of ignition in magneto electric ignition apparatus. These apparatus may be 15 divided into two different groups according to the basic principle on which they operate. According to one principle the entire iron yoke is shifted together with the interrupter around the axis of the apparatus. This has 20 the advantage that the most favorable phase of the current can always be utilized for ignition, but it has the great drawback that a considerable space must be left available for the rotation of the yoke corresponding to 25 the maximum angle of regulation of the point of ignition, so that the dimensions of the apparatus are considerably increased thereby. The other principle employed in the known mechanisms for regulating the 30 point of the ignition, consists in this that the yoke is stationary while the interrupter is alone shifted. In apparatus of this kind a different phase of the current is utilized for the ignition for each adjustment of the interrupter. The adjustment of the ignition apparatus of this kind has the advantage of 35 requiring only a small space, but it is limited because from a determined point of adjustment onward the current curve is no 40 longer of sufficient value for the ignition.

The present invention has now for its object to provide an improved mechanism which combines the advantages of both kinds of regulation of the point of ignition, 45 while avoiding their drawbacks.

The characteristic feature of the present invention consists in this that the yoke and the interrupter are adapted to be shifted together as a whole, while the interrupter is 50 also adapted to be shifted independently in relation to the yoke.

An arrangement of this kind allows of effecting the maximum required regulation of the point of ignition by shifting the yoke

(which requires space) but only to such an extent as is absolutely necessitated in respect of the shape of the current curve, while the other portion of the regulation of the point of ignition is effected by shifting the interrupter relatively to the yoke.

An embodiment of the present invention is illustrated by way of example in the accompanying drawings.

Figure 1 shows in full lines the intermediate position of the interrupter *b* and of the yoke *c* carrying the coil *d*, the extreme position in which the interrupter *b* and yoke *c* can reach in either direction being shown in dotted lines.

Fig. 2 shows the middle position of the interrupter *b* and yoke *c*.

Fig. 3 shows the farthest position of the interrupter *b* that can be reached by its displacement to one side, the yoke *c* being displaced as in Fig. 1, by the $\alpha/2$ and the interrupter *b* relatively to the yoke additionally by the angle α' , so that in this direction a total displacement of the interrupter by the angle $\alpha/2+\alpha'$ is reached. In this figure the spring *e* is shown compressed to its greatest extent.

Fig. 4 shows the extreme position of interrupter and yoke when moved in the opposite direction.

The construction of the mechanism consists essentially in the feature that it can be displaced as a whole in both directions, with the aid of a manually operated lever *a* fitted to the interrupter. On the lever *a* being rotated in one direction a projection *f* carries along with it a stop *f* fixed to the yoke *c* at the point *h* attached to the yoke *c*. On its rotation in the opposite direction the projection *f* on the interrupter *b* carries with it a stop *h* in one with the yoke *c*, which latter contacts with stops *g* on the casing. But the interrupter *b* is further displaced automatically in the same direction by reason of a further compression of the spring *e* taking place between the projection *f* on the interrupter *b* and the stop *g* on the frame, without the yoke *c* taking part in this further rotation.

The operation of the mechanism is effected in the following manner:

By clockwise rotation of the hand lever *a*, the interrupter *b* which is rotatable around the axis of the apparatus, can be shifted

together with the yoke c that carries the winding d , from the mid position shown in Fig. 2 to both sides through the angle $\alpha/2$ as far as the stops on the casing g (Fig. 1). For shifting the apparatus in a counter-clockwise direction it is not possible to rotate the lever a any further, but it is possible to rotate the interrupter b through a further angle α' in a clockwise direction, the yoke c remaining stationary (Fig. 3). In this movement a compression takes place of the spring e which is located between a stop f on the interrupter casing g and a stop h fixed to the yoke c . In rotating back the lever a from this position, the spring e is unstressed and first the interrupter is shifted through the angle α' relatively to the yoke, until the stop f on the interrupter meets the stop h which is likewise fixed to the yoke c . By this means on further rotation of the lever a , the yoke c is carried around with it and rotated past the mid position (Fig. 2) as far as the stop g (Fig. 4) on the opposite side.

This invention thus allows of regulating the time of ignition to an extent which, owing to the non-symmetry of the current curve, extends through an angle of $\alpha/2$ to one side of the mid position shown in Fig. 2, and through an angle of $\alpha/2 + \alpha'$, on the other side of the said mid position, that is to say, through a total angle of $\alpha + \alpha'$. A shifting of the yoke and consequent increase in the dimensions of the apparatus is then necessitated only as required by the angle α .

The remaining portion α' of the angle of regulation is dealt with by the automatic shifting of the interrupter relatively to the yoke without thereby causing the point of ignition to come within unfavorable phases 40 of the current.

What I claim is—

1. In mechanism for regulating the point of ignition in magneto electric apparatus a construction in which a circular hand operated interrupter member is provided with a projection on the periphery thereof, said projection engaging with a recess in a yoke concentrically mounted in the same plane as such interrupter member, a spring located 50 in said recess which permits the interrupter to be moved through a further angle, which movement allows of regulating the time of ignition to the extent required, substantially as shown and described. 55

2. In mechanism for regulating the point of ignition in magneto electric apparatus the combination of parts for effecting the feature as claimed comprising a hand operated interrupter member with a projection 60 formed thereon and a yoke piece for carrying a coil attached thereto, a concentric segmental ring provided with a recess which forms a stop for said projection and a spring in said recess adapted to allow a differential movement between the adjacent parts, substantially as shown and described. 65

In testimony whereof I have signed my name to this specification.

E. HURLIMANN.
